ATTORNEY

UNITED STATES PATENT OFFICE.

LEWIS A. PLATT, OF WATERBURY, CONNECTICUT, ASSIGNOR TO THE PLATT BROTHERS & COMPANY, OF SAME PLACE.

BUTTON.

SPECIFICATION forming part of Letters Patent No. 363,676, dated May 24, 1887.

Application filed April 6, 1887. Serial No. 233,873. (No model.)

To all whom it may concern:

Be it known that I, LEWIS A. PLATT, of Waterbury, in the county of New Haven and State of Connecticut, have invented a certain 5 new and useful Improvement in Buttons, of which I declare the following to be a full, clear, and exact specification, reference being had to the accompanying drawings, forming part thereof.

10 This invention is in the nature of an improvement in bar buttons; and the invention consists of a bar button constructed in the manner herein particularly shown, described, and claimed.

15 In the accompanying sheet of drawings, Figure 1 is a top view of my button. Fig. 2 is a section in the plane $\alpha\alpha$, Fig. 1. Fig. 3 is an under side view. Fig. 4 is a side view of a cross-bar with a curved center. Fig. 5 is an 20 under side view of said cross-bar. Fig. 6 is a side view of a cross-bar with a straight center.

Similar letters of reference indicate like parts in the several views.

25 This invention particularly relates to an improvement in so-called "bar buttons"—that is, buttons with a central perforation spanned by a bar of metal, over which the threads are passed in sewing the button to the garment. Buttons of this character are common, old, and 30 well known, and my invention relates only to what I believe to be an improvement on these old and well-known buttons; and the improvement, referring to the drawings, consists, first, in making the back-plate A of the button with 35 a hub, a , a central perforation, b , and an inner projecting flange, B , surrounding the perforation. This inner flange projects inwardly a convenient distance, as in Fig. 2. The back-plate having the construction described, a bar, C , is made of wire or other material, curved in its center, c , as in Fig. 4, or 40 straight, as in Fig. 6, and having notches d

formed near the extremities of the bar and flattened ends e . The notches d are so formed in the bar C that when that bar is placed diametrically across the opening b of the back A these notches will receive a part of the edge of the flange B, and the entering of the edge of this flange in this way will keep the bar in place to the extent of preventing its lateral 50 movement.

45 When the bar is fitted to the back-plate in the manner described, the center c of the bar, when curved, protrudes downward to some extent through the opening b , and so affords an 55 easy passage for the needle and thread over the bar when the button is being sewed onto the garment.

50 The flattened ends e of the bar C have a double function: They permit the fitting in and 60 the securing of the face-plate D by not projecting in a manner to obstruct the fitting of the face-plate to the back, and they possess the other function of affording flat bearing surfaces against which the under surface of the 65 front plate, D, may bear and so tightly confine the bar C in position when the face-plate is finally secured to the back-plate of the button, as in Fig. 2.

Having now described my invention, what 70 I claim as new, and desire to secure by Letters Patent, is—

In a button, the following elements in combination: a back-plate, A, formed with a hub, a , and a central perforation, b , surrounded by 75 a flange, B, a bar, C, with notches d , so located as to receive the edge of the flange B, and with flattened ends e , and a face-plate, D, as and for the purpose described.

LEWIS A. PLATT.

In presence of—

JOHN P. KELLOGG,

THOMAS F. DOUGHERTY.
